UNITED STATES PATENT OFFICE.

RANDOLP MCBEE, OF WASHINGTON, DISTRICT OF COLUMBIA.

STOP-BOX.

SPECIFICATION forming part of Letters Patent No. 704,656, dated July 15, 1902.

Application filed January 7, 1902. Serial No. 88,812. (No model.)

To all whom it may concern:

Be it known that I, RANDOLP MCBEE, a citizen of the United States, residing at Washington, in the District of Columbia, have invented new and useful Improvements in Stop-Boxes, of which the following is a specification.

This invention relates to certain new and useful improvements in stop-boxes; and it has for its object, primarily, to provide a construction which will prevent the cover from becoming detached and lost—such as, for instance, by the influences of frost, &c. It is desirable that the tops to stop-boxes be screwed in position in order to prevent their easy removal, and thus allow dirt and other foreign substance to get into the box, yet such tops or caps should be easily removable when necessary.

Broadly stated, my invention consists in the provision of a cap or top and the part into which it screws of unlike metals, the part engaging with the cap or top being preferably of brass, although other material may be employed, some material that is non-corrodible. The non-corrodible material is preferably of brass in the form of a ring, which in one of its forms is seated in a recess or cavity, where it is removably held in any suitable manner. This ring is interiorly threaded to receive the exterior threads on the depending portion of the cap or top. This ring is of such a form as to prevent its turning when once in position and is easily removable for replacement or other purposes.

Other objects and advantages of the invention will hereinafter appear, and the novel features thereof will be specifically defined by the appended claims.

The invention is clearly illustrated in the accompanying drawings, which, with the numerals of reference marked thereon, form a part of this specification, and in which—

Figure 1 is a perspective view of my improved stop-box, the cover being shown removed. Fig. 2 is a view of the box with the cover in position. Fig. 3 is a top plan view with the cover removed, the ring being in position. Fig. 4 is a similar view with the ring removed. Fig. 5 is a vertical section on the line 5 5 of Fig. 2. Fig. 6 is a detail view of the cover on a larger scale. Fig. 7 is a per-

spective view of the ring removed. Fig. 8 is a view, partly in elevation and partly in vertical section, showing a modified form of construction. Fig. 9 is a substantially central vertical section through the upper part of a box of a slightly-modified form.

Like numerals of reference indicate like parts throughout the several views.

Referring to the drawings, 1 designates the box proper, which may be of any of the well-known forms, except as hereinafter specified. As my improvements pertain solely to the top portion of the box, a detailed description of the other portion is not deemed necessary.

Referring first to the form seen in Figs. 1 to 7, inclusive, it will be seen that the box at its upper end is formed with the usual enlargement 2, within which is the substantially horizontal annular flange 3, upon which is designed to rest the removable ring 4. As seen best in Fig. 4, this flange is recessed upon its upper face, as at 5, and in the present instance is shown as formed with the diametrically opposite enlargements or cavities 6 to receive the projections 7 on the ring 4. The ring 4 is preferably of brass, although other non-corrosive material may be employed, and in this instance it is shown as provided with the before-mentioned projections 7, corresponding in shape to the cavities or enlargements 6, so that when in place the ring is held against movement within the enlargement of the box. The ring is screw-threaded upon its inner wall, as seen in Figs. 5 and 7 at 8, and at opposite sides is provided with the openings 9 for the reception of the bolts 10, which are provided with the screw-heads 11, adapted to be seated in the countersinks of the said openings, the said bolts passing through the openings or slots 11' in the opposite faces of the flange 3, as seen in Fig. 5, where they receive the nuts 12. The ring is thus firmly held in place against vertical or lateral movement, yet can be readily removed when desired.

13 is the cap or cover. It may be of the usual form, having the word "Water" or "Gas" thereon, as seen in Fig. 1, and it is designed to rest upon the annular shoulder 14, formed at the upper end of the box and provided with a lug 15 to receive a wrench or suitable tool whereby it may be readily

turned. The cap or cover is formed with the depending portion 16, which is exteriorly screw-threaded, as seen in Fig. 6, to engage the threads of the ring, as seen in Fig. 5. In practice, the ring being secured in position, the cap is placed in position and the threads of its depending portion engaged with the threads of the ring and the cap or cover then screwed down. The brass of the ring contacting with the depending portion of the cover or cap keeps the latter from contact with the iron of the box at that point, and the result is that the cover will never rust into the ring, but may at all times be relied upon as being in condition to be easily removed by unscrewing the same.

The invention is capable of embodiment in a variety of forms other than that above described. For instance, the ring may be otherwise held in position. In Fig. 9 I have shown one convenient way. In this form the upper portion of the box is formed interiorly with the flange 17, having the offset or shoulder 18, the flange at its lower portion being interiorly screw-threaded, as seen at 19, to receive the threaded portion 20 of the ring 21, the said ring being provided at its upper end with the exterior annular flange 22, resting upon the shoulder 18, as seen in Fig. 9. The cap or cover is provided with the screw-threaded depending portion engaging the threads of the ring the same as in the form seen in Fig. 5.

In Fig. 8 is shown another form of ring 23, having the holes 24 for the reception of the bolts or other means which are to secure it in position, and this ring is formed to receive the casted threads 25 on the cap or cover 26, which are provided in lieu of the cut threads on the covers in the other forms in order that the cover may be cast, if desired, with the threads instead of the threads being cut as is customary in this class of devices. The result is practically the same. The rings shown in Figs. 8 and 9 are, like those previously described, formed of brass or some suitable non-corrodible material for the same purpose.

As will be evident from the above, the stop-box herein described may be used for either water or gas and other purposes.

From the above it will be seen that I have devised a novel form of stop-box capable of manufacture at minimum cost, yet most effi-

cient for the purposes for which it is intended, and while the structural embodiment of my invention as herein disclosed is what I at 55 the present time consider the preferable it is evident that various changes, variations, and modifications may be made without departing from the spirit of the invention or sacrificing any of its advantages, and I therefore do not wish to be restricted to the details of construction herein set forth, but reserve the right to make such changes, variations, and modifications as come properly within the scope of the protection prayed. 60 65

What I claim as new is—

1. A stop-box having an internal horizontal supporting-flange recessed upon its upper face, a ring removably supported in said recess against rotary and outward movement, 70 and a cap having a depending screw-threaded portion screwed into said ring, substantially as described.

2. A stop-box having a flange with recess with enlargements, a ring independent of the box and having projections fitting said enlargements, means for detachably securing the ring in position, and a cap or cover having a depending screw-threaded portion to engage the threads of the ring, substantially as 80 described.

3. As an improved article of manufacture, the stop-box herein described, the same comprising the box proper having enlargement at its outer end, an internal angular horizontal flange within said enlargement and having a recess upon its outer face with diametrically disposed enlargements, a screw-threaded ring supported on said flange and having projections fitting said enlargements, means detachably securing said ring in position with its upper face flush with the upper face of the flange, and a cap or cover having screw-threaded depending portion engaged with the threads of the ring, the screw-threaded engaging portions, being of different metals, one of which is non-corrodible, substantially as described. 90 95

In testimony whereof I affix my signature in presence of two witnesses.

RANDOLP MCBEE.
